UNITED STATES PATENT OFFICE

LLEWELLYN ALBERT MAYO, OF HANNAFORD, NORTH DAKOTA

HIGHWAY-GUARD STRUCTURE

Application filed December 11, 1928. Serial No. 325,349.

This invention relates to a guard structure adapted to be placed along public highways, grades and bridges, for the purpose of minimizing automobile accidents, and injury to 5 persons and property.

An object of the invention is the provision of an improved type of device, a plurality of which are respectively attached to spaced posts or standards along the side of the highway, and designed and adapted to hold a cable or like element up from the highway and away from the line of posts lengthwise of the highway, to present a continuous smooth contact surface which may be 10 encountered by automobiles or other vehicles traveling on the highway, and be prevented from leaving the highway, and also to prevent serious damage to automobiles or other vehicles coming in contact therewith while 15 traveling on the highway in a direction paralleling the cable.

Another object of the invention is to provide a device of the indicated character which facilitates stringing of the cable, which 20 securely holds the cable in place, and which is of simplified and durable construction.

The nature of the invention and its distinguishing features and advantages will appear when the following specification is 25 read in connection with the accompanying drawing, in which—

Figure 1 is a side view of the upper end of a post with a cable holding device of the present invention applied thereto.

Fig. 2 is a plan view.

Fig. 3 is a central vertical sectional view.

Fig. 4 is a horizontal sectional view taken on the line 4—4 of Fig. 3.

Fig. 5 is a view of the jaws of the device 40 in gripping engagement with a portion of the cable.

In accordance with the present invention a plurality of spaced posts or standards are arranged along the side of a public highway 45 at different locations, such as sharp curves, steep grades, and on bridges. Each post or standard will have attached thereto a similar device adapted to cooperate with others to support a cable or like element lengthwise 50 along the highway paralleling the same away

from the line of posts. Referring now more particularly to the drawing, it will be apparent that there is shown the upper end of a post or standard 10, which may be of any suitable height and cross sectional shape and 55 size, and in the present instance is a wooden post round in cross section. The cable holding device attached to the post 10 consists of an arm 11 having a part 12 which conforms to the shape of the post and a jaw 13. The part 12 has holes which respectively receive a fastening element such as a screw bolt 14 extending through upper end of the post 10, to hold the arm 11 in rigid position projecting toward the highway. The arm 11 has a recess 60 15 in the under side thereof, a hole 16, and also a bore 17 for purposes to appear. A bolt 18 is employed and has a jaw 19 at one end, and the opposite end is threaded as at 20. The bolt 18 is of a diameter to fit the bore 17 65 in the arm 11, and is of a length to extend through the upper end of the post 10, the latter being provided with a transverse hole 70 for that purpose. The jaw 19 on the bolt 18 is receivable in the recess 15 which conforms 75 to the shape of the jaw 19. It will be apparent that the jaw 19 is movable or slideable 80 relatively to the jaw 13, and is adapted to cooperate therewith to grip a cable or like element 21. The jaws 13 and 19 are designed 85 and constructed to grip the cable in such a manner that a continuous smooth contact surface indicated at 22 will be presented. The jaw 19 by being movable relatively to the jaw 13 may be brought to a position to enable 90 a cable to be brought between both jaws to be gripped thereby, or to release the cable when necessary or whenever the occasion arises. A nut 23 is screwed on the end 20 of the bolt 18 to hold it and therefore the jaw 19 against movement.

In order to aid the jaws 13 and 19 in holding the cable a wedge or key 24 may be driven between the jaws 13 and 19 and the cable 21 95 is shown most clearly in Figs. 1 and 3.

In order to protect the upper end of the post 10 and to distribute the strain on the bolt 18 there is provided a cap 25 having depending lugs 26 and 27 arranged diametrically 100 opposite each other. The lug 26 is receivable 103

in the hole 16 in the arm 11, and the lug 27 contacts with the side of the post 10 when the cap is in place on the top of the post. The lugs 26 and 27 have holes respectively in alinement and receive the bolt 18. The nut 23 is screwed up against the lug 27 and securely fastens the parts together.

It is to be understood that alternate relatively high and low posts or standards may be located along the side of the highway, each post or standard having a device of the character described, making it possible to support two cables up from the highway at different elevations, away from the line of the posts or standards, and disposed lengthwise of or parallel to the highway. It is also to be understood that a single cable may be supported in the manner described. Where two cables are used, one will be disposed low enough to be below the hubs of the automobile wheels, and the other well to the top of the wheels. Where one cable is used it may be arranged to come either below or above the hubs of the automobile wheels, preferably below the hubs.

25 I claim:

1. The combination with a post, of a post, of a cap arranged on the top of the post, said cap having lugs arranged opposite each other, an arm rigidly secured to said post and projecting laterally therefrom, said arm having a jaw formed integral therewith, one of said lugs fitting into a hole in the arm, and the other lug depending in contact with said post, a bolt extending loosely through the post, arm and lugs and having sliding movement relative thereto, a jaw on one end of said bolt, the bolt being of a length to bring the jaw thereon into a gripping relationship with respect to the other jaw, and a nut in threading engagement with said bolt to hold its jaw in the gripping relation with respect to the other jaw.

2. A clamping device comprising a cap having lugs arranged opposite each other, an arm positioned on one of said lugs, said arm having a jaw, a bolt extending loosely through said lugs and arm, a jaw on one end of said bolt, the bolt being of a length to bring the jaw thereon into a gripping relationship with respect to the other jaw, and a nut in threading engagement with said bolt and engageable with one of said lugs to hold the jaw on said bolt in the gripping relation with respect to the other jaw.

55 LLEWELLYN ALBERT MAYO.
